F. P. ROBERT.

Inventor

By his Attorney

Norman J. Whitaker

UNITED STATES PATENT OFFICE.

FREDERIC P. ROBERT, OF LYNNBROOK, LONG ISLAND, NEW YORK.

WRENCH.

1,407,578.

Specification of Letters Patent. Patented Feb. 21, 1922.

Application filed April 2, 1921. Serial No. 458,164.

To all whom it may concern:

Be it known that I, FREDERIC P. ROBERT, a citizen of Switzerland, and a resident of Lynbrook, Long Island, in the county of Queens and State of New York, have invented a new and useful Wrench, of which the following is a specification.

My invention relates to wrenches and its principal object resides in the provision of

10 a wrench which is self adjustable.

It is a further object of the invention to provide a self adjustable wrench which will positively grip a nut or other object.

15 A further general object of the invention is to provide a wrench of comparative simplicity and which at the same time is simple in operation and inexpensive to manufacture.

20 With the preceding and other objects that will be apparent from the following specification, the invention consists in the novel combination of elements, constructions and operations to be specifically pointed out, claimed and illustrated in the accompanying drawing wherein,

Figure 1 is a side elevation of my improved wrench in inoperative position,

Fig. 2 is a similar view showing the wrench engaged with a nut, and,

25 Fig. 3 is a top plan view of the wrench.

Referring in detail to the drawing where in similar characters of reference denote corresponding parts throughout the several views, the numeral 5 designates a stationary or rigid jaw provided with serrations 6 upon its inner face at the forward end thereof. The jaw 5 is formed with, at its opposite end, a shank or handle 7.

The numeral 8 designates a swinging movable jaw provided with serrations 9 upon its inner face. As illustrated in Fig. 1 this jaw 8 is normally disposed at an oblique angle with respect to the longitudinal axis of the jaw 5 with its forward end projecting beyond the forward end of the jaw 5. Pairs of links 10 are pivoted to the outer face of the jaws 5 and 8 and as shown in Fig. 2 each pair slightly diverge from the other pair.

30 In order to normally swing the links 10 forwardly to cause the jaw 8 to be held into

engagement with a nut or other object, a contractile spring 11 is provided which has its ends connected to transverse pins 12 carried by the links 10.

From the disclosure it will be seen that the jaw 8 will be yieldably held against the nut or other object and that the wrench will readily adjust itself to objects of various sizes.

It is to be understood that the form of my invention herein shown and described is to be taken as a preferred example of the same, and that various changes in the shape, size and arrangement of parts may be resorted to without departing from the spirit of the invention or the scope of the subjoined claims.

Having thus described my invention, what I claim as new and desire to secure and protect by Letters Patent of the United States is:

35 1. A wrench comprising a rigid jaw, a movable jaw arranged in opposed relation thereto, pairs of links having their ends pivotally connected with the opposite faces of the jaws, and a contractile spring arranged between the jaws and having its ends disposed in close proximity to the movable jaw so that the force of the same acting on the movable jaw will be in a plane parallel to the direction of travel of the movable jaw.

40 2. A wrench comprising a rigid jaw, a handle extending from one end thereof, a movable jaw opposed to the rigid jaw and movable in a plane which is oblique to the longitudinal axis of the rigid jaw, pairs of links arranged in divergent relation and having their ends pivoted to the outer faces of the jaws, pins extending transversely of each pair of links, and a coil spring disposed parallel to the swinging jaw when the latter is in normal position and having its ends connected to the pins, the spring normally holding the movable jaw in advance of the rigid jaw to yieldably hold the movable jaw into engagement with the object to be gripped.

FREDERIC P. ROBERT.
